(57) **CLAIM**

The ornamental design for a scraper blade, as shown and described.

DESCRIPTION

FIG. 1 is a perspective view for a scraper blade;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof; and,
 FIG. 7 is a bottom plan view thereof.
 The broken lines in the figures illustrate portions of the scraper blade that form no part of the claimed design.

1 Claim, 7 Drawing Sheets
